UNITED STATES PATENT OFFICE.

CHARLES F. HOOFER, OF SEATTLE, WASHINGTON.

ELECTRIC OPERATING MEANS FOR FLANGE-OILERS.

1,389,247.

Specification of Letters Patent. Patented Aug. 30, 1921.

Application filed November 22, 1919. Serial No. 340,007.

To all whom it may concern:

Be it known that I, CHARLES F. HOOFER, a citizen of the United States, and resident of Seattle, county of King, and State of Washington, have invented certain new and useful Improvements in Electric Operating Means for Flange-Oilers, of which the following is a specification.

My invention relates to a means for automatically operating an auxiliary mechanism, such as a track or flange oiling device, whenever the car strikes a curve.

The object of my invention is to provide means whereby the lateral swing of the trolley when the car strikes a curve, may be utilized to bring into action such an oiling mechanism.

In the accompanying drawings I have shown the mechanism whereby I now prefer to carry out my invention.

Figure 1 is a diagram showing the relationship of the various parts employed in carrying out my invention.

Fig. 2 is a plan view of the current controlling and applying device.

Fig. 3 is a section showing the manner of using the air controlling device.

This invention has been particularly designed for controlling the application and use of such devices as is shown in my Patent No. 1,278,657 of September 10, 1918, for a track lubricator. In the drawings 13 represents the pneumatically operated oil distributing or feeding device, as shown in said patent and 9 the tank, or other source of supply of air under pressure by which the oil distributing device is operated. As the specific structure of these parts is immaterial, no details thereof will be here given.

A valve 11 is inserted between the sections 10 and 18, of the pipe which conveys the air from the reservoir 9 to the distributor 13. This valve is electrically opened, by any suitable electrical apparatus. As shown it is closed by a spring 1 and is opened when the current is applied to the coil which is in the casing 6.

Adjacent to the base of the trolley pole 5 is secured a conducting ring 3 having finger 30, which is in electrical connection with the feed wire 8 leading to the electrically operated valve 11. The base of the trolley pole has a ring or disk 4 which has two diametrically opposite recesses 40, so located as to be opposite the finger 30 when the trolley

ley is on the wire. If the trolley is not reversible, only one recess is needed.

The width of the recesses 40 may be so gaged that as soon as any determined angle 60 of swing has been reached, contact will be made between the ring 4 and the finger 30, thus causing current to flow through the conductor 8 to the valve operating coil 6. This will apply the operating air to the distributor 13.

7 represents a resistance placed in the circuit to limit the current flow to the coil 6.

What I claim as my invention is:—

1. A flange oiling device comprising 70 means carried by a car for placing oil upon the flange, electrical means for controlling the action of said oiling mechanism, and a switch mechanism actuated to close the electrical circuit by the side swing of the trolley. 75

2. A flange oiling device comprising means carried by a car for placing oil upon the flange, electrical means for controlling the action of said oiling mechanism, a switch for controlling the electric circuit 80 having one part mounted to swing with the trolley and the other mounted on the car to be engaged by the first part when the trolley pole is swung laterally.

3. A flange oiling device comprising 85 means carried by a car for placing oil upon the flange, electrical means for controlling the action of said oiling mechanism, and a switch mechanism actuated to close the electrical circuit by the side swing of the 90 trolley.

4. A flange oiling device comprising means carried by a car for placing oil upon the flange, electrical means for controlling the action of said oiling mechanism, a 95 switch for controlling the electric circuit having one part mounted to swing with the trolley and the other mounted on the car to be engaged by the first part when the trolley pole is swung laterally. 100

5. A flange oiling device comprising means carried by a car for placing oil upon the flange, electrical means for controlling the action of said oiling mechanism, a switch for controlling the electric circuit 105 comprising a member mounted to turn with the trolley base and having the outline of a circle indented at two diametrically opposite points, and a member fixed upon the car and extending into one of said indentations 110 without contacting with its sides when the trolley is centrally positioned.

6. A track oiling device comprising air operated means carried by a car for applying oil to the track a valve controlling the application of air to said mechanism, and 5 means for electrically controlling the action of said valve.

7. A track oiling device comprising an air operated mechanism for applying oil to the track, a valve controlling the operating air, 10 electric means for controlling said valve and means for controlling the supply of electricity by the side swing of a trolley.

8. A track oiling device comprising an air operated mechanism for applying oil to the track, a valve controlling the operating air, 15 electric means for controlling said valve and a switch for controlling the application of current, said switch having one part carried by the car body and the other by the trolley 20 pole to contact with the first by the swing of the trolley to one side of the central position.

9. In an oiling device, an air operated oil distributing mechanism, a valve controlling 25 the application of the operating air to said distributing mechanism, an electric controlling means for said valve and means for automatically energizing said electric controlling means by the swinging of a member 30 relative to the car body due to the curvature of the track.

10. In a track oiling device, air operated

oil distributing mechanism, an electrically controlled valve controlling the application of air to said oil distributing mechanism, 35 and a switch controlling the application of current to said valve, one part of said switch being carried by the car body and the other by the trolley base.

11. In an oiling device for cars, in combination, a source of electricity, means for making and breaking the circuit thereof automatically actuated by the swing of the trolley when rounding a curve, a source of fluid pressure for operating the oiling device 40 and an electromagnetically controlled fluid pressure valve for controlling the operating fluid pressure.

12. In a car oiling device, in combination, 45 a series of oil supplying mechanisms and actuating means therefor, an electromagnet for controlling the application of the actuating means to each of said supplying mechanisms, an electric circuit having connections with said electromagnets, means automatically actuated by the side swing of the trolley for making and breaking the circuit when rounding curves, and oil delivery pipes 50 extending from the oil supplying mechanisms.

Signed at Chicago, Illinois, this 29th day 55 of October, 1919.

CHARLES F. HOOFER.
